UNITED STATES PATENT OFFICE.

JAMES S. REID, OF CLEVELAND, OHIO, ASSIGNOR, BY MESNE ASSIGNMENTS, TO THE EATON AXLE & SPRING COMPANY, OF CLEVELAND, OHIO, A CORPORATION OF OHIO.

CLOSURE.

Application filed October 13, 1926. Serial No. 141,342.

This invention relates to improvements in closures and more particularly, in closures of the type provided with air chambers which are vented to the outside atmosphere and to the inside of the devices being closed.

Heretofore, in closures of this type, the air chambers thereof have been vented to the outside atmosphere by apertures in the outer walls of the closures, which not only mar the appearance of the closures but also leave said apertures unprotected so that they often become fully or partially closed by dirt and the like.

The object of the present invention is to provide an improved closure having a novel arrangement of vent means for the air chamber thereof, so that while said chamber is vented to the outside atmosphere and to the inside of the device being closed, just as in prior closures of this type, the outer wall of the closure is free of perforations.

Further objects of the invention are in part obvious and in part will appear more in detail hereinafter.

In the drawings, which represent one suitable embodiment of the invention, Fig. 1 is a vertical sectional view of my improved closure applied to the tubular neck portion of a tank or the like; Fig. 2 is a bottom plan view of the closure; Fig. 3 is a top plan view of the closure; Fig. 4 is a top plan view of the tubular neck portion of Fig. 1; and Fig. 5 is a view similar to Fig. 1 but taken at ninety degrees thereto.

In Figs. 1 and 5 of the drawings, the closure is shown applied to the cylindrical neck or filler portion 1 of an automobile fuel or other tank 2, said neck portion being either an integral part of said tank or separate therefrom, as shown, and provided with a lateral base flange 3 for securing to said tank.

Said neck portion is provided at its upper end with an inwardly extending, substantially horizontal flange 4 which terminates in a depending flange 5. At two diametrically opposite points, flanges 4 and 5 are cut away, as indicated in Fig. 4, to provide two openings or passageways 6, through which the locking fingers of the closure are adapted to be passed, as will later appear. The cutting away of portions of flanges 4 and 5 provides two depending flange portions 5

of substantially semi-circular form and the bottom edges of these flange portions are inclined to provide two cams 7 with which the locking fingers of the closure co-operate in effecting detachable locking connection of the closure and the tank neck portion. At the rear ends of these cams, the flange portions 5 are each provided with a depending lug or projection 8, which provide stops for the locking fingers of the closure as said fingers ride up the cams 7. Preferably, said cams are provided adjacent said stop portions with recessed dwell portions (not shown), upon which dwell portions the locking fingers of the closure are adapted to rest when the closure is in fully seated position upon the tank neck portion. 70

Coming now to the closure forming the subject matter of the present invention, said closure includes an outer wall and an inner wall separated to provide an air chamber 10 therebetween. The outer wall includes a substantially circular, dome-shaped top portion 11 and a depending marginal or skirt portion 12 which is slightly larger in diameter than the tank neck portion 1. The inner wall includes a substantially flat, circular disk 13, the outer edge of which is crimped or otherwise suitably secured to the outer wall at the junction of the top and skirt portions thereof. Said disk is provided with a centrally disposed, upwardly extending annular portion 14 terminating in a circular offset portion 15, said portions 14, 15 forming a downwardly opening recess 16. Within this recess and engaging the offset portion 15 is the substantially flat body portion 17 of a locking or securing member, the two opposed, curved edge portions 18 of said body portion being crimped or otherwise suitably secured to the upwardly extending disk portion 14. The body 95 portion of said locking member is provided at each of its two opposed straight edge portions 19 with an inherently resilient locking or securing finger portion 20 extending downwardly and outwardly from said body portion, as clearly indicated in Fig. 5.

The closure is applied to the tank neck portion 1 in the usual manner of bayonet joint connections, the locking or securing fingers 20 of the closure being passed down 100 through the passageways 6 of the neck portion

tion. The closure is then turned in a clockwise direction which causes the locking fingers thereof to ride up the cams 7 with yielding effect, the rotary movement of the closure being continued until said fingers strike the stop portions 8. To remove the closure, it is only necessary to turn it in the reverse direction, as will be readily understood.

10 Coming now to the vent means for the air chamber 10 of the closure, said air chamber is vented to the inside of the neck portion 1 (and hence to the tank 2) by one or more apertures in the central zone of the inner wall 13, and which may be located in one or both of those parts of the disk offset portion 15 not covered by the body portion 17 of the closure locking member.

15 In the embodiment here shown, said disk offset portion is provided with two apertures 23, each of which is arranged above one of the downwardly and outwardly extending closure locking fingers 20, so that said apertures are baffled by said fingers.

20 25 The means for venting said air chamber 10 to the outside atmosphere comprises one or more apertures or openings in or near the outer edge portion of the closure disk 13. In the present embodiment, two such 30 openings 24 are shown, which are formed by suitably notching the outer edge portion of said disk, as clearly indicated in Figs. 1 and 2. Inasmuch as the skirt portion 12 of the closure outer wall is slightly larger 35 in diameter than the tank neck portion 1, an annular channel or space 25 is provided between said portions. This space is, of course, in direct communication with the outside atmosphere and in communication 40 with the air chamber 10 by means of the disk notches 24.

45 It will thus be seen that the air chamber 10 is effectively vented to both the inside of the device to be closed and to the outside atmosphere, and at the same time, the outer wall of the closure is free of disfiguring apertures. Moreover, the apertures 24 are 50 protected by the outer wall of the closure and are therefore not likely to become closed by dirt or the like. They also serve admirably as drain vents or outlets for paint, enamel, lacquer or any other coating material applied to the cap as a protective coating or for ornamentation. Any such 55 material which may find its way into the chamber 10, as by immersion of the cap in a bath of the coating material, readily drains away and neither becomes trapped in said chamber or tends to clog the several vent openings, particularly because the vents 60 65 70 75 80 85 90 95 100 105 110 115 120 125 130 135 140 145 150 155 160 165 170 175 180 185 190 195 200 205 210 215 220 225 230 an annular gasket 28, of cork, leather or the like, and slightly smaller than the disk 13 so that the vent notches 24 in the outer edge portion of said disk are not covered by said gasket. When the closure is applied to the tank neck portion, as shown in Figs. 1 and 5, said gasket lies between an annular sealing seat 30 which surrounds the recess in the central zone of the closure disk 13 and the inwardly extending, horizontal flange 4 of the tank neck portion. When the closure is removed from said tank neck portion, the gasket is prevented from becoming disassociated from the closure by the outwardly extending closure locking fingers 20, although other and additional means may be provided, if desired.

What I claim is:

1. A closure for receptacle necks, comprising inner and outer walls having portions separated to provide an air chamber therebetween, securing means associated with the inner wall, vent means in said inner wall providing communication between said air chamber and the inside of the neck when the closure is applied to the neck, said securing means being so arranged as to provide a baffle for the second named vent means.

2. A closure for receptacle necks, comprising an inner wall and an outer wall, securing means carried by said inner wall, and vent means through said inner wall providing communication between the outside atmosphere and the inside of the neck when said closure is applied thereto, said securing means being so arranged as to baffle said vent means.

3. A closure for receptacle necks, comprising an imperforate outer wall, securing means for releasably maintaining said outer wall in assembled relation with a neck, an annular gasket located between the closure and the neck, and vent means permitting flow of air from the inside of said neck above and around said gasket to the outside atmosphere.

4. A closure for receptacle necks, comprising

ing an imperforate outer wall structure, an inner wall structure spaced therefrom to form an air chamber and extending generally transversely to the closure axis, said inner wall structure being provided with vent means located and arranged to provide communication, when the closure is applied to the neck, between the air chamber and the inside of the neck, and other vent means providing communication between the air chamber and the outside atmosphere around the edge of the outer wall structure.

6. A self contained removable closure for receptacle necks, comprising separated inner and outer wall structures, the former having an annular seat cooperating with the neck for sealing purposes and the latter being imperforate, and vent means lying within the imperforate outer wall structure and opening outside of said annular seat providing communication, when the closure is applied to the neck, from the inside of the neck and around and above the seat to the outside atmosphere.

7. A closure for receptacle necks, comprising a generally cup shaped body having a skirt adapted to sleeve over the neck with a channel therebetween and outer and inner wall portions separated to form an air cham-

ber therebetween, and vent means from the inside of the neck to said chamber and from the chamber to said channel.

8. A closure for receptacle necks, comprising a sleeve like skirt portion, an imperforate outer wall portion and an annular sealing seat portion extending inwardly from the skirt portion and lying in a plane transverse to its axis and having an opening in its central zone, and vent means near the outer periphery of the seat portion and lying within the outer wall and skirt portions and affording communication around and above the seat from said opening through said vent means to the outside atmosphere.

9. A closure for receptacle necks, comprising an outer wall structure having a dome shaped imperforate portion, an inner wall spaced therefrom to form an air chamber narrowing outwardly toward its periphery, vent means through the central zone of the inner wall to said chamber, and other vent means from the narrow peripheral portion of said chamber around the periphery of the outer wall structure to the outside atmosphere.

In testimony whereof I hereby affix my signature.

JAMES S. REID.
